UNITED STATES PATENT OFFICE

WALTER EVERETT MOLINS, OF DEPTFORD, LONDON, ENGLAND

CARTON FOR CIGARETTES AND LIKE ARTICLES

Application filed January 20, 1931, Serial No. 510,030, and in Great Britain February 4, 1930.

This invention is for improvements in or relating to cartons for cigarettes and similarly shaped articles, and has for its object the provision of a carton which will adequately protect the cigarettes and yet avoid the imperfections which are inherent in the cigarette packings which are at present employed.

With cigarette packets at present employed, the mere operation of opening the packet does not present the cigarettes ready for removal from the package, but some further operation has to be performed, for example, the folding back of a flap in the case of a slide and shell packet to enable the cigarettes to be removed. This is the case even where the cigarettes are not enveloped in foil.

The present invention consists of a carton for cigarettes and like articles arranged to accommodate two superimposed rows of cigarettes when the package is closed, and which, when opened, automatically separates the two rows from one another and simultaneously completely uncovers the free ends of each row of cigarettes.

The invention also consists of a carton for cigarettes and the like of the type which comprises two pockets each arranged to accommodate a single row of cigarettes with the axes arranged at right angles to the mouth of each pocket, and united by a flap in such a manner as to permit the same to be opened out into line with the open ends of the pockets directed towards one another, and to extend across the open ends of the two pockets and form the sole closure element for the same when one pocket is folded upon the other, characterized by portions of the inner broad panels of the pockets being folded upon themselves within the pockets to form openings at the open ends of the pockets which display the free ends of the cigarettes located therein.

Further, the present invention consists of a carton for cigarettes and the like, of the type which comprises two pockets each arranged to accommodate a single row of cigarettes with the axes arranged at right angles to the mouths of each pocket, and united by a flap in such a manner as to permit the same to be opened out into line with the open ends of the

pockets directed towards one another and to extend across the open ends of the two pockets and form the sole closure element for the same when one pocket is folded upon the other, characterized by each pocket being so connected to the said flap that when the carton is opened, the free ends of the cigarettes in each pocket are automatically uncovered so as to present a free finger-hold for each cigarette from either side of the pocket.

Again, for the satisfactory packing of cigarettes it is essential that the cigarettes must be adequately wrapped and protected against atmospheric and outside influences, and for this purpose cigarettes are usually enveloped in an outer covering of tin foil which, when the packet is to be used often, forms a source of annoyance to the user, inasmuch as the same has to be either unwrapped from around the cigarettes or torn away so as to provide access to the cigarettes in the carton, and once the foil has been torn away the cigarettes are no longer protected, and the appearance of the package is immediately disfigured.

Further, with the method at present employed of enveloping cigarettes in tin foil, it has been found that once a cigarette has been removed from the package, it is difficult to replace the same without either damaging the cigarette or the foil, or both.

Where cigarettes are enveloped as a batch in an envelope of tin foil, it is necessary to unfold the foil from around the cigarettes in order that a cigarette may be removed, whereupon, if the cigarettes are to be thereafter adequately protected, the foil must be refolded about the cigarettes, otherwise they lose their flavour. Where, however, a batch of cigarettes have a strip of foil folded about the same so as to leave the sides free, it is necessary when removing a cigarette from a package, to lift one end of the foil from around the cigarettes, to remove the desired number of cigarettes from the package and thereafter replace the foil about the ends of the cigarettes which is very often inconvenient and completely neglected by the average consumer of cigarettes.

Further, if it is necessary to replace a

cigarette into the package it is found that usually the cigarette catches upon one end of the foil which is thereafter pressed into the bottom of the package by the continued movement of the cigarette, thus removing the protection which has hitherto been afforded by the foil.

Again, where the cigarettes are wrapped in more than one row in an outer envelope of 10 foil, the end of the envelope is usually opened and the cigarette or cigarettes removed by gripping the end of the same by means of the finger nails and thereby more often than not destroying the end of the cigarette. In 15 all cases gloves must be removed to secure a cigarette.

Again, in cigarette containers comprising a box having a hinged lid, it is necessary to open the lid, fold back the foil from one end 20 of the cigarettes, remove a cigarette by gripping the same between two fingers and thereafter replacing the foil, in which case the cigarette is sometimes damaged and the foil scarcely ever replaced in its correct position. Thus it will be seen from the foregoing that all cigarette packages in which the cigarettes are enveloped, or wrapped in foil, disadvantages are inherent in the packages which either cause the cigarettes to be 25 damaged when being removed from the package, or the foil is destroyed as the cigarettes are being removed.

It is an object of the present invention to wrap and adequately protect cigarettes in 30 two rows in a carton by means of a strip of foil in such a manner as to permit immediate and automatic access to the cigarettes when the carton is opened and avoid any unfolding or tearing or fingering of the foil by the user, and yet preserve the protective appearance of the foil enveloping the cigarettes so that the cigarettes may be removed from, and re-inserted into a package without disturbing the foil wrapping which is arranged 40 about the same, and for this purpose there is provided a foil wrapping for a carton for cigarettes and the like of the type which comprises two pockets united by a flap in such a manner as to permit the same to be 45 opened out into line with the open ends of the pockets directed towards one another and to extend across the open ends of the two pockets and form the sole closure element for the same when one pocket is folded upon the 50 other which will completely eliminate all the disadvantages hereinbefore referred to in connection with cartons at present employed.

The invention therefore also consists of a 55 carton comprising two block ended pockets 60 hinged together by a flap which also constitutes the sole closure member of the carton characterized by portions of the inner broad panels of the pockets being folded upon themselves within the pockets to form openings at the open ends of the pockets which

display the free ends of the cigarettes located therein, the folded portions also forming protective means for the ends of the strip of foil arranged around the batch of cigarettes disposed within each pocket.

A further object of the invention is to provide means whereby the hinged flap is stiffened or reinforced so that the hinge portion of the packet shall be practically as strong as the block ended portions of the two separate pockets.

The invention will be more particularly described with reference to the accompanying drawings, in which:—

Fig. 1 shows a blank from which a carton 80 is constructed in accordance with this invention is formed.

Fig. 2 shows a perspective view of a completed carton in the open position.

Fig. 3 is a central section of Fig. 2.

Fig. 4 is a perspective view of a closed carton.

Fig. 5 shows a side elevation of the packet illustrating the method of stiffening the hinge, and

Fig. 6 shows another form of blank from which the carton may be formed.

Referring to the drawings, the carton is preferably formed from a rectangular strip of cardboard 1 of such a length that when the two ends 2 thereof are folded into pockets, the same are united by a flap 3 which will hinge the two pockets together in the manner hereinbefore referred to.

The free ends 2 of the blank are slit at 4 100 so as to provide portions which may be folded upon the main body of the blank so as to extend over the ends of a strip of foil superimposed upon the blank, or in the case where foil is not employed, the material between 105 the slits 4 may be entirely removed to expose the cigarettes.

The portions between the slits 4 when folded over the ends of the foil provide openings 5 in the broad face of each pocket so as to 110 expose from one side of the pocket the free ends of the cigarettes 6 which are disposed with their axes at right angles to the mouth of the pocket.

The carton is formed by superimposing a 115 strip of foil 5* in the manner hereinbefore referred to and thereafter folding the slit portions upon the ends of the foil so as to extend over the same. Two batches of cigarettes are thereupon fed on to the blank so 120 that the axes of the same are disposed in the direction of the longitudinal axis of the blank, and the ends of the blank are thereafter folded about each batch of cigarettes into a U formation so as to form a U shaped 125 block ended pocket about each batch of cigarettes with a strip of foil extending around the carton in the manner shown in Fig. 3.

It will be observed that when the two pockets are folded one upon the other a cov- 130

ering of foil is disposed between the cigarettes and the outer walls of the closed container except at two side walls thereof, whereas, when the carton is open the ends of each 5 batch of cigarettes are freely exposed and ready of access.

The broad panels 7 of the pockets are preferably slit at 8 and scored at 9 in order to increase the effective width of the hinge to 10 expose the free ends of the cigarettes and permit them to be gripped from either side of the pocket, and easily withdrawn by the consumer. If desired, the panels 2 may have a design 10 cut therein in order to expose the 15 foil which may be embossed in any desired manner.

The method of reinforcing the hinge member consists in securing, by means of gum, a piece of cardboard 11, of the same dimensions as the hinge, so that when the pockets are folded as in Fig. 5, the stiffener 11 forms a kind of strut between the outer walls of the carton, and prevents the same from being crushed in the pocket of the user.

25 In some cases the portions of the ends of the blank which are turned over may be slit to form a number of spring fingers 12 which function in the manner described in my prior British Patent No. 288,739.

30 Referring to Fig. 6 of the drawings, it will be seen that in this case the carton is formed from a rectangular blank 13 having side extensions 14, which side extensions are folded over on to the main body of the blank so as to 35 form a double pocket container of the type described. In this case the material 15 between the two side extensions 14 is folded over on to the hinged portion 16, and gummed thereto to form the stiffening for the hinge, as 40 in the previous case.

In a packet of this character, a strip of foil may be arranged to extend beyond each end of the blank, whereupon a batch of cigarettes is fed to either end of the blank. The blank 45 is then fed through folding mechanism which first wraps the foil in the direction of the axes of the cigarettes, but holds the ends of the foil a predetermined distance from the cigarettes, whereafter the side extensions of the 50 blank are folded across the blank in a direction at right angles to the cigarettes and the portion between the slots 4 is then folded around the end of the foil, whereupon the side extensions of the blank and the foil are 55 folded upon the cigarettes so as to produce a foil lined carton comprising two pockets united by a flap each having a single row of cigarettes with the axes thereof located at right angles to the mouths of the pockets.

60 It will be seen that according to the invention there is provided a carton for cigarettes arranged to accommodate two rows of cigarettes so that when the carton is opened, the respective rows are separated from one 65 another and arranged in such a manner that

the free ends of the cigarettes of each row present sufficient finger hold for each cigarette of the two rows to be easily removed from the carton, and when foil is employed and the carton is closed, the cigarettes are 70 almost completely enveloped in foil, but are automatically exposed to view with a clear portion of their ends available from either side of a pocket as a finger hold when the carton is opened, and the foil is arranged within 75 each pocket so that the free ends thereof are protected, thus enabling a cigarette to be replaced in the package once the same has been removed, without the possibility of the cigarette or the foil becoming damaged by 80 such an action.

What I claim as my invention, and desire to secure by Letters Patent is:—

1. A carton comprising two block ended pockets hinged together by a flap which also constitutes the sole closure member of the carton, characterized by portions of the inner broad panels of the pockets being folded upon themselves within the pockets to form openings at the open ends of the pockets which display the free ends of the cigarettes located therein, the folded portions also forming protective means for the ends of the strip of foil arranged around the batches of cigarettes disposed within each pocket. 95

2. A paper carton for cigarettes and the like which comprises two pockets each formed so as to hold a single row of cigarettes with the axes of the cigarettes disposed at right angles to the mouth of the pocket, a flap hingedly connecting the two pockets in such a manner as to permit the same to be opened out into line with the open ends of the pockets directed towards one another, and to extend across the open ends of the pockets to form the sole closure element for the same when one pocket is folded upon the other, that face of each pocket which lies adjacent the other pocket in the folded condition of the carton being slit adjacent the corners of the pocket to provide a tab, the tab being folded into and extending downwardly within the pocket to yieldingly engage the cigarettes for retaining the latter against unintentional displacement, 110 and an inner liner of foil extending within each pocket around the cigarettes and under the tab, whereby the foil is retained against displacement by the tab. 115

3. A carton comprising two block ended pockets hinged together by a flap which also constitutes the sole closure member of the carton, characterized by portions of the inner broad panels of the pockets being folded upon themselves within the pockets to form openings at the open ends of the pockets which display the free ends of the cigarettes located therein, the folded portions also forming protective means for the ends of the strip of foil arranged around the batches of cigarettes 120 125 130

disposed within each pocket, the flap being prolonged by slits adjacent each of the four corners which extend down the outer panels of the folded carton.

5 In testimony whereof I hereunto affix my signature.

WALTER EVERETT MOLINS.
